[57] CLAIM

The ornamental design for a material lift vehicle body, as shown and described.

DESCRIPTION

FIG. 1 is a perspective view of the front and one side of a material lift vehicle body showing our new design;

FIG. 2 is a perspective view of the rear and opposite side thereof;

FIG. 3 is a fragmentary perspective view of the rear portion thereof;

FIG. 4 is a fragmentary perspective view of the operator cab and rear portion thereof; and

FIG. 5 is a top plan view thereof.

The broken lines in the drawings are for illustrative purposes only.
